UNITED STATES PATENT OFFICE

160,930

STAND FOR BEVERAGE DISPENSERS

Robert B. Duff, Crookston, Minn.

Application February 24, 1949, Serial No. 1,054

Term of patent 14 years

(Cl. D44—26)

To all whom it may concern:

Be it known that I, Robert B. Duff, a citizen of the United States, residing at Crookston, in the county of Polk and State of Minnesota, have invented a new, original, and ornamental Design for a Stand for Beverage Dispensers, of which the following is a specification, reference being made to the accompanying drawing, forming a part hereof.

In the drawing:

Fig. 1 is a top plan view of a stand for beverage dispensers embodying my new design;

Fig. 2 is a side elevational view thereof; and

Fig. 3 is a top plan view of the same.

I claim:

The ornamental design for a stand for beverage dispensers, substantially as shown.

ROBERT B. DUFF.
